UNITED STATES PATENT OFFICE.

WILLIAM J. BLATT, OF HOLLIDAYSBURG, PENNSYLVANIA.

INTERNAL-COMBUSTION ENGINE.

1,265,596.

Specification of Letters Patent.

Patented May 7, 1918.

Application filed October 28, 1916. Serial No. 128,271.

To all whom it may concern:

Be it known that I, WILLIAM J. BLATT, a citizen of the United States, residing at Hollidaysburg, in the county of Blair and State 5 of Pennsylvania, have invented new and useful Improvements in Internal-Combustion Engines, of which the following is a specification.

This invention relates to internal combustion engines, the object in view being to produce an engine of the two-cycle type in which companion cylinders are arranged at an angle to each other resembling engines of the V type, the said angularly related cylinders having a single or combined combustion chamber in which the charges are exploded by a single ignition device, the expanding charge acting simultaneously on both pistons and the latter being so connected with the crank shaft that one of the pistons will always operate slightly in advance of the other piston thereby producing an economical two cycle engine in which the exhaust port is opened before the inlet port 25 and said exhaust port is also closed before the inlet port is closed.

A further object in view is to produce a two cycle high speed internal combustion engine the construction of which results in 30 a valveless motor having the economy and flexibility of the ordinary four cycle motor without the complicated valve mechanism therefor.

With the above and other objects in view, 35 the invention consists in the novel construction, combination and arrangement of parts, as herein described, illustrated and claimed.

In the accompanying drawings:—

Figure 1 is a section through the improved 40 engine taken transversely of the crank shaft and diametrically of the companion cylinders.

Fig. 2 is a section taken at right angles to Fig. 1, in line with the crank shaft and 45 diametrically of adjacent cylinders.

Fig. 3 is a fragmentary, horizontal section in line with the outlet port.

Referring to the drawings 1 designates the crank shaft which is journaled in bearings 2 fitted in the crank case 3, the lower section 4 of which is detachably fastened to the upper or main section by means of bolts 5 inserted through lugs or flanges 6 on the crank case sections. In Fig. 2, two of such 55 crank cases 3 are shown but are separated entirely from each other in order to admit

of the necessary crank case compression. While I have shown two units in Fig. 2, it will be understood that the engine may be constructed with one unit or as many units 60 as may be desired.

Each unit comprises two companion cylinders 7 and 8 having a common water jacket 9 and a common combustion chamber 10, 11 and 12. The cylinder 7 is provided with a 65 by-pass 12 having an inlet port 14 to receive the charge compressed in the crank case, and an outlet port 15 which forms the intake port for the cylinder 10. The cylinder 9 is provided with an outlet port 16 which constitutes the exhaust port of the pair of companion cylinders. In the intervening portion 17 between the cylinders 7 and 8 there is a large inlet chamber 18 to which the gas is conducted by an intake pipe 19 having 70 attached thereto a suitable carburetor 20. An inlet port 21 leads from the chamber 18 into the cylinder 7 and is uncovered by the piston in that cylinder as the latter approaches the outer limit of its movement. 75

Within the cylinder 7 is a reciprocatory piston 22, another reciprocatory piston 23 working in the cylinder 8. A rod 24 connects the piston 22 with the crank arm 25 of the shaft 1 and another connecting rod 85 26 connects the piston 23 with said crank arm. Both of the connecting rods 24 and 26 are connected to the same crank arm 25 as indicated in Figs. 1 and 2. 27 designates an ignition member shown in the form of an 90 ordinary spark plug. The water jacket is provided with inlet and outlet connections 28 and 29 respectively. 30 designates a fly wheel fast on the crank shaft 1.

In the operation of the engine, as the 95 piston 22 approaches the outer limit of its movement it uncovers the port 21 and on account of the suction or partial vacuum created in the crank case and lower portions of the cylinders, a charge of explosive mixture is admitted to the crank case. In the return or inward movement of the pistons said charge of mixture is compressed in the crank case and forced through the port 14 into the by-pass 13. As the piston 22 approaches the inner limit of its movement, it uncovers the port 15 and the compressed charge is then liberated into the combustion chamber 10, 11 and 12. At such time the exhaust port 16 is closed by the piston 23. 100 In the outward movement of the pistons, the charge is compressed in the combustion 105 110

chamber and fired driving the pistons inward on their working strokes. Before the port 15 is uncovered, the exhaust port 16 is uncovered by the piston 23 thereby permitting 5 the burned gases to be exhausted. Just after this occurs, the piston 23 starts on its outward movement and covers the exhaust port 16 just as the piston 22 uncovers the intake port 15. Then the piston 22 starts to return 10 and closes the intake port 15. The charge of mixture then trapped in the combustion chamber is compressed as before. This operation is repeated in each cycle of the engine. It will thus be seen that the engine is of 15 the valveless two cycle type but differs from the ordinary two cycle engine in that it employs companion cylinders so arranged in relation to each other and having intake and exhaust ports so arranged in relation 20 to the cylinders and the movements of the pistons that there is no waste of gas even at low speeds, the engine is capable of high speed work and possesses the economy and flexibility of the more complicated four 25 cycle internal combustion engine.

I claim:—

An internal combustion engine embodying companion cylinders arranged in angular relation to each other, a cylinder head com-

mon to both cylinders, a crank case common 30 to both of said cylinders, a combustion chamber common to both of said cylinders, one of said cylinders being formed with a by-pass leading from the crank case to said combustion chamber, a spark plug located 35 centrally of said common cylinder head, the other cylinder being formed with an exhaust port, pistons working in said cylinders, a common crank shaft, and connecting rods between said pistons and the same crank 40 arm of said shaft, the arrangement of the intake and exhaust ports being such that one piston travels in advance of the other piston, causing the exhaust port to be opened before the inlet port and also to be closed 45 while the inlet port is opened, and a charge receiving chamber located between the cylinders and formed by the walls thereof, the wall of said charge receiving chamber being formed with a port leading to the 50 crank case and covered and uncovered by one of said pistons, the last named port being so located that in one position of the piston in the charging cylinder, said port is closed while the discharge end of the by 55 pass is open.

In testimony whereof I affix my signature.
WILLIAM J. BATT.
